HYBRID RING MULTICOUPLER FOR A PLURALITY OF PAIRS OF TRANSMITTERS
Charles E. Woicott, El Cajon, Calif., assignor to Whittaker Corporation, a corporation of California
Filed Mar. 28, 1963, Ser. No. 268,682
11 Claims. (Cl. 325—129)

The present invention relates to means and techniques useful in coupling a plurality of high frequency sources to a common load and to a system embodying such means and techniques wherein specifically a plurality of transmitters are coupled to a common antenna system.

The systems disclosed herein involve the use of one or more hybrid rings to couple a plurality of radio transmitters operating within a 2-30 megacycle frequency band to a single antenna.

Multicoupling functions are performed using low loss, air dielectric, coaxial transmission lines at these relatively low frequencies.

There has long existed a need for a multicoupling system which uses only a single antenna with a plurality of transmitters operating in the frequency range of 2-30 megacycles per second and feeding such single antenna. Prior arrangements operating in this frequency band used lumped constant reactive elements arranged into filter or tuned resonant circuitry, thereby imposing certain limitations on the system such as, for example, permissible bandwidth, power-handling capacity, and number of transmitters which may be coupled to a single antenna.

An important feature of the present invention involves the concept of using hybrid rings operating in conjunction with coaxial lines or other elements having distributed impedances at these relatively low frequencies in the 2-30 megacycle range. Heretofore, the hybrid ring has been employed primarily as a mixer at microwave frequencies in radar and related systems and has also been used to a limited extent to combine power in television transmitting systems operating in the very high or ultra-high frequency range.

It is therefore a general object of the present invention to provide improved means and techniques for efficiently coupling a plurality of transmitters to a single antenna without substantially any transmitter interaction or power loss.

A specific object of the present invention is to provide a system of this character in which two adjacent channel operating transmitters are efficiently coupled to a single antenna without the necessity of maintaining a fixed percentage of frequency separation between the two channels.

Another specific object of the present invention is to provide a system of this character which does not require tuning adjustments to be made during small adjacent channel frequency changes.

Another specific object of the present invention is to provide a system of this character which allows the carrier frequency of any transmitter of the system to be adjusted without having to readjust the associated adjacent channel transmitters.

Another specific object of the present invention is to provide a system of this character in which the coupling system imposes a small insertion loss and minimizes the possibility of failure due to voltage breakdown.

Another specific object of the present invention is to provide a system of this character which uses hybrid rings

2

with suitable impedance matching between transmitters and the common antenna.

Another specific object of the present invention is to provide a system of this character which provides a low voltage standing wave ratio throughout the entire operating band.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

FIGURE 1 illustrates a system embodying features of the present invention;

FIGURE 2 illustrates a form of hybrid ring which may be incorporated in the systems disclosed herein;

FIGURE 3 shows a portion of a hybrid ring for achieving a phase reversal whereby the four arms of the ring may be equally spaced 90 degrees apart as shown in FIGURES 1 and 4 instead of as in FIGURE 2;

FIGURE 4 serves as an illustration of another system embodying features of the present invention;

FIGURE 5 represents the electrical equivalent circuit of the arrangement shown in FIGURE 3 at the normal operating frequency of the hybrid ring of which such arrangement forms a part.

Each of the arrangements described herein uses one or more six quarter-wavelength coaxial hybrid rings exemplified in FIGURE 2 and having the arms 1, 2, 3, and 4 extending from the ring portion 5. As dimensioned in FIGURE 2, the arm 1 is spaced one-quarter of a wavelength from arm 2 and three-quarters of a wavelength from arm 3; arm 2 is spaced a quarter wavelength distance from arm 4; and arm 4 is spaced a quarter wavelength distance from arm 3. Thus, at the operating frequency there is no direct coupling between arms 1 and 4 or between arms 2 and 3 since the spacing in each case is one-half of one wavelength. This is due to the electrical length of the ring elements being such that if a frequency source is coupled to arm 1, the electrical length to arm 4 around the side containing arm 3 is one wavelength, and the electrical length to arm 4 around the side containing arm 2 is one-half wavelength, thus resulting in wave cancellation at the junction of arm 4. Thus, both arm 1 and arm 4 are isolated from each other when simultaneously supplied with voltages at a similar frequency.

A voltage source S_A is coupled to arm 1 and a voltage source S_B is coupled to arm 4, and when the frequency of these two sources is identical, there is a theoretical maximum isolation between arms 1 and 4. This isolating characteristic of the hybrid ring is used to overcome the problem of adjacent channel frequency separation which prevails in existing multicoupler systems. The present multicoupling system employing a hybrid ring combines the outputs of two transmitters to allow the transmitters to operate either at the same frequency or at slightly different frequencies under power conditions without danger of transmitter burnout.

It is preferred that the three-quarter-wavelength element of the six quarter-wave ring shown in FIGURE 2 be substituted by a portion having a physical length of one quarter-wavelength and this is accomplished by a reversal in phase in such element, such reversal in phase being accomplished, for example, by the arrangement shown in FIGURE 3 which is described later. By thus providing a

phase reversal, the three quarter-wavelength dimension then actually has a quarter-wavelength physical length and in such case, the arms 1, 2, 3 and 4 are equally spaced physically around the ring with a 90-degree angular separation between the same as illustrated in FIGURES 1 and 4.

Various means may be used to accomplish such phase reversal in the three quarter-wavelength arm and, as shown in FIGURE 3, this is accomplished by the use of a pair of aluminum discs 10 and 11 to which opposite ends of a coil 12 are connected. These discs 10 and 11 are connected also respectively to ends 6A and 6B of the interrupted inner conductor 6 (FIGURE 2) of the coaxial ring 5. The discs 10 and 11 and coil 12 are within a cylindrical housing 14 of metal which is joined to the outer metal tubular portion of ring 5; and insulation 15 surrounding the discs 10, 11 and coil 12 insulates these elements from the outer metal portion of the ring. This construction thus preserves the coaxiality of the inner and outer metal portions of the ring and results in the three quarter-wavelength arm to have a physical length of one quarter-wavelength but yet an electrical length of three quarter-wavelengths.

The arms 1, 2, 3, and 4 in FIGURE 2 are correspondingly numbered in FIGURES 1 and 4. It will be seen that in FIGURE 1 there are provided eight six-quarter electrical wavelength rings 5, each having a different nominal operating frequency with two pairs of four rings each. Thus, a first pair comprises a 20-megacycle, 10-megacycle, 5-megacycle, and 2.5-megacycle rings and the other pair comprises 28-megacycle, 14-megacycle, 7-megacycle, and 3.5-megacycle rings.

The number 1 and number 4 arms of each ring are, as shown, connected through a corresponding filter to a corresponding high-frequency source, i.e. transmitter, which is either unmodulated or modulated in accordance with well known techniques. Thus, using the 20-megacycle ring as an example, its number 1 arm is coupled to the transmitter 20 through a filter circuit 21 and the number 4 arm is coupled to the transmitter 24 through filter circuit 25. The transmitter 20 is adjusted to a frequency within the range of 16.5 to 23.5 megacycles and the other transmitter 24 may be adjusted to a frequency in the same range as indicated in the drawings. This frequency range of operation, as indicated also for the other transmitters, has a midfrequency which corresponds to the nominal frequency of the hybrid ring to which such transmitters are coupled through arms 1 and 4. These connections or couplings to the hybrid rings are, of course, through coaxial connections.

The number 3 arms of each of the 20, 10, 5, and 2.5-megacycle rings are coupled to spaced points 30, 31, 32, and 33, respectively, along a transmission line 35 which is shorted at one of its ends 36 and which includes the adjustable sections 35A, 35B, 35C, and 35D, these sections being adjustable to achieve the electrical spacings of such arms 3 to the shorted end 36 of the transmission line. Likewise, the number 2 arms of the 20, 10, 5, and 2.5-megacycle rings are connected respectively to points 40, 41, 42, and 43 along the transmission line 45 which has one of its ends shorted at 46 and which comprises adjustable lengths 45A, 45B, 45C, and 45D to obtain the quarter-wavelength spacings indicated in the upper portion of FIGURE 1. The transmission lines 35 and 45 have their other ends coupled to the input terminals 38 and 48, respectively, of an antenna system 50 mounted on a grounded mast 51.

The other 28, 14, 7, and 3.5-megacycle rings are similarly coupled with the number 1 and number 4 arms of each being coupled to a separate transmitter and with the number 2 and number 3 arms of each being coupled to spaced points along the transmission lines 80 and 70, respectively. One end of each of the lines 70 and 80 is shorted at 71 and 81, respectively, and the other ends 75

of such lines 70 and 80 are coupled respectively to the antenna input terminals 72 and 82. The transmission line 70 comprises adjustable sections 70A, 70B, 70C, and 70D; and the transmission line 80 comprises the adjustable sections 80A, 80B, 80C, and 80D.

The arms number 3 of each of the 20, 10, 5, and 2.5-megacycle rings are spaced an electrical length from the shorted transmission line end 36 a distance equal to one quarter-wavelength of the nominal frequency of the corresponding ring; and likewise, the number 2 arms of each of these rings are spaced an electrical length from the shorted transmission line end 46 a distance equal to one-quarter of a wavelength of the frequency of the corresponding ring, this being indicated at the upper portion of FIGURE 1. For example, the arm 3 of the 20-megacycle ring is electrically spaced from the shorted end 36 a distance of one quarter-wavelength at 20 megacycles; the arm 3 of the 10-megacycle ring is spaced one quarter of a wavelength at 10 megacycles from the same shorted end 36; and likewise, the arm 2 of the 20-megacycle ring is spaced electrically a distance equal to one-quarter of a wavelength at 20 megacycles from the shorted end 46 and the arm 2 of the 10-megacycle ring is spaced electrically a distance from such shorted end 46 equal to one quarter of a wavelength at 10 megacycles. This corresponding relationship is also true with respect to the 28, 14, 7, and 3.5-megacycle rings. For example, the number 2 and number 3 arms of the 28-megacycle rings are spaced electrically one quarter of a wavelength from the shorted ends 81 and 71, respectively, at the frequency of 28 megacycles; and the arms 2 and 3 of the 14-megacycle ring are spaced electrically from the shorted ends 81 and 71 a distance equal to one-quarter of a wavelength at 14 megacycles. Thus, each of the rings is coupled to a transmission line one quarter of a wavelength from the shorted end of the line with the result that each transmitter "sees" a high impedance when looking backward down the line towards the corresponding shorted line and "sees" a frequency multiple of one-half of a wavelength when looking up the line towards the antenna. It is recalled that transmission line theory dictates that a quarter-wavelength line "inverts" the independence at the end of the line and that half-wavelength line "repeats" the impedance at the end of such half-wave line.

Thus, wave transmission from the hybrid rings is forwardly to the antenna system without substantially any interaction between the individual transmitters which are effectively isolated one from the other with the transmission lines providing isolation between rings and the ring itself isolating the particular pair of transmitters coupled thereto through the arms 1 and 4.

In the modification shown in FIGURE 4, the 20-megacycle, 10-megacycle, 5-megacycle, and 2.5-megacycle rings are cascaded and this figure serves also to illustrate the manner in which the other four 28, 14, 7, and 3.5-megacycle hybrid rings are cascaded and interconnected to the same segmented antenna as in FIGURE 1. Here again, as in FIGURE 1, a pair of transmitters, operating within the frequency range of that particular ring, is coupled to such ring through arms 1 and 4. The highest frequency ring has its number 2 arm coupled to the number 3 arm of the next lowest frequency ring, with the number 3 arm of the highest frequency ring being coupled to the antenna terminal 38 and with the arm 2 of the lowest frequency ring being coupled to the antenna terminal 82. In this case the ring isolates those two sources which are connected thereto through arms 1 and 4 and also the quarter-wavelength sections of such ring provide isolation of these same transmitters from transmitters connected to the other rings through corresponding arms 1 and 4.

Preferably each source is connected to its corresponding ring through an impedance-matching network and a tuned circuit which is tuned to the same frequency as

that transmitter which is coupled by such tuned circuit. Thus, for example, the transmitter 90, adjusted to operate at a frequency within a range of 16.5 to 23.5 megacycles, is coupled through transmission line 91, having an impedance of 70 ohms, to a tapped coil 92. The sheath of the line 91 is connected to the grounded end of coil 92 and the inner conductor of the line is connected to a tap 94 on coil 92. A second tap 95 on the coil is connected through a series resonant circuit comprising adjustable coil 97 and adjustable capacitor 98 to arm 4. A capacitor 99 is connected between ground and the tap 95. The other transmitters are likewise connected to corresponding arms of corresponding hybrid rings as shown in FIGURE 4.

This arrangement provides improved impedance matching between a frequency source and the corresponding hybrid ring input port or arm. The impedance-matching network comprising the tapped coil 92 allows greater flexibility in performance. Two primary benefits are obtained through the use of such matching network. First, the most important is the impedance match condition achieved between a wide range of transmitter output impedances and the 70-ohm ring port impedance. Secondly, the network described provides frequency selectivity which is adjustable to only the passive frequency, and this presents a high impedance to any other frequency source which "looks" backward on the line connected to the ring port. Thus, preferably impedance matching and an additional isolation characteristic is achieved prior to application of the transmitter input to the input of the ring.

In considering impedance matching to a ring, it should be noted that the impedance looking into a junction from a side arm of the ring is the sum of the impedances seen looking both ways into the ring junction. The characteristic impedance of the ring, therefore, is generally greater in value than that of the side arm by a factor of the square root of two. It is desirable, from a manufacturing point of view, for both the ring and side arm coaxial lines extending therefrom to have the same outer conductor diameters and the impedance values may be selected through choice of the diameter of the coaxial center conductor. The ratio between outer and inner diameters of the ring conductors may, for example, be 3.57 although it is understood that this ratio may be changed to achieve different impedance conditions.

Preferably, for purposes of flexibility and versatility in operation and adjustment, the rings and branch lines are made so as to be adjustable in length using so-called line-stretchers involving a so-called trombone construction involving sliding fits between sections of the inner and outer conductors. Preferably, such trombone construction allows a twenty percent change in physical length to allow optimum tuning under all possible operating conditions.

Preferably, the particular type of matching network specifically illustrated in FIGURE 4 is incorporated in the system shown in FIGURE 1.

In the cascade arrangement of hybrid rings shown in FIGURE 4, adjacent ones of the rings are interconnected by one-half wavelength sections as indicated for the flow of energy therebetween, it being noted that the half-wavelength lines between the arms or legs 2 and 3 are one-half wavelength long at the higher frequency of the two interconnected rings. Thus, for example, the number 2 and number 3 arms of the 20- and 10-megacycle rings, respectively, are interconnected by a line which is one-half wavelength at 20 megacycles. While, as discussed above in connection with FIGURE 2, there is isolation between terminals 2 and 3 of the same ring and at the nominal frequency of that particular ring, this is not the case when frequencies other than the nominal frequency of that particular ring is considered, this being so due to the fact that the pi phase section in each three

quarter-wavelength arm provides a phase shift of 180° only at the particular nominal frequency of that hybrid ring in which the pi section under consideration is located. This will be seen from FIGURES 3 and 5 wherein FIGURE 3 illustrates the physical construction of the pi phase section of the three-quarter arm and FIGURE 5 illustrates the equivalent circuit of the construction shown in FIGURE 3 which is the equivalent circuit only at the particular ring frequency. The equivalent circuit shown in FIGURE 5 is illustrated as having a pi configuration with a series inductance arm 140 and a pair of shunt-connected capacitors 141 and 142 shunting respectively what may be termed the input and output terminals of the network; and additionally, due to the distributed capacitance of the coil 12 of FIGURE 3, there is present an additional capacitance 143 represented as having one of its terminals connected to the midpoint of inductance 140, i.e. of coil 12. This construction of the pi section shown in FIGURE 3, with its placement being indicated by the Greek letter pi in FIGURE 4, allows, for example, energy from the 10-megacycle ring to be transferred from the number 2 and number 3 arms of the 20-megacycle ring and thence to the antenna terminal 38. Likewise, energy from both transmitters coupled to the arms 1 and 4, respectively, of the 5-megacycle ring is transferred to the antenna terminals 38 and 82 through the 2.5-megacycle, 10-megacycle, and 20-megacycle rings. This is so since the pi sections in the 2.5-megacycle, 10-megacycle, and 20-megacycle rings do not impose a 180-degree phase reversal of energy at 5 megacycles.

The antenna used in either the system shown in FIGURE 1 or FIGURE 3 is preferably of the sectionalized type which is suitably terminated such that the voltage standing wave ratio does not exceed 3 to 1 over the 2-30 megacycle range. Preferably one antenna is stacked directly on top of another to avoid the configuration of a spaced array. When, as is preferred, the multicoupling system comprises adjustable line lengths, the phase is controllable at any operating frequency such that the radiation angle of the sectionalized antenna may be adjusted and controlled at all frequencies of operation.

Preferably, the antenna combines the characteristics of the cage and discone antennas, with the lower frequency part of the 2-30 megacycle band division being radiated by the cage portion of the antenna and the high frequency part of the division by the discone. Thus, as illustrated, the antenna consists of two cage-discone antennas stacked one above the other and with one inverted. The two section cages are used for the 2-8 megacycle part of the band and the two section conic portions are used for the 8-30 megacycle part of the band.

The arrangements disclosed herein are thus useful for combining the output power of up to sixteen, 5,000-watt CW or 10,000-watt modulated radio transmitters within a 2-30 megacycle frequency band. This is done by providing symmetrically fed circuits having a single plane of symmetry which passes through the two input ports or arms. If one transmitter is retuned for proper loading, or additional frequency adjustment, instability transients have little or no effect on other transmitters, thereby eliminating the necessity of a readjustment of all transmitters as in prior art arrangements wherein the loading and tuning is complicated by the introduction of transients that necessitate a complex retuning and readjustment procedure. By isolating one transmitter from other transmitters, loading and tuning of a particular transmitter may be accomplished on an individual basis, a highly desirable condition.

It will thus be seen that the multicoupling band combiner consists of eight coaxial line hybrid rings grouped into two independent cascade series interconnected with coaxial intercostal lines. The conventional three-quarter wavelength section of each hybrid ring is replaced by a pi phase shifter and a quarter-wavelength section of co-

axial line. This reduces the long line length and allows the hybrid ring frequency bandwidth to be controlled. Control of the hybrid ring bandwidth and the sub-division of nominal frequencies for the two, four-ring cascades provides sixteen input channels covering a 2-30 megacycle band. The two hybrid ring cascades have the following nominal frequencies:

Number 1 Cascade	Number 2 Cascade
2.5 MC	3.5 MC
5.0 MC	7.0 MC
10.0 MC	14.0 MC
20.0 MC	28.0 MC

The two input ports of each hybrid ring are isolated approximately 42 db from each other. Thus, the 15% channel frequency separation normally mandatory with conventional multicouplers does not apply to the hybrid ring multicoupler. The hybrid ring system, due to its close frequency isolation characteristics, overcomes the problems of frequency pulling, signal priming, mutual synchronization and the transmitter burn-out hazards of former multicoupler systems. Maximum isolation is achieved when two adjacent channel transmitters are tuned to the same frequency.

The sixteen multicoupled transmit channels are grouped in pairs which correspond to the two input ports of each of the eight hybrid rings. Both ports of each hybrid ring have the same bandwidth and cover the same channel frequencies. The subdivision, therefore, provides the following channel frequencies:

Cascade Number	Nominal Ring Frequency in Megacycles	Channel Number	Channel Frequencies in Megacycles
1-----	2.5	1	2.062-2.938
2-----	3.5	2	2.062-2.938
1-----	5.0	3	2.896-4.125
2-----	7.0	4	2.896-4.125
1-----	10.0	5	4-12.5, 5.75
2-----	14.0	6	4.125-5.75
1-----	20.0	7	5.75-82.5
2-----	28.0	8	5.75-82.5
		9	8.25-11.75
		10	8.25-11.75
		11	11.55-16.5
		12	11.55-16.5
		13	16.5-23.5
		14	16.5-23.5
		15	23.1-32.9
		16	23.1-32.9

Each of the sixteen transmitter input channels contains a channel matching filter. This matching filter functions to match the 50-ohm hybrid port input impedance between 25 to 75 ohms, such that, the transmitter effectively sees a resistive load. The matching filter contains a series resonant circuit which is adjusted by a single control to the frequency being transmitted. The off-frequency isolation of this series resonant circuit plus the inherent power-split characteristics of the hybrid provides a minimum 42 db isolation from other hybrid rings in the cascade series. The frequency separation of hybrids in the cascade is noted to be such that isolation is always achieved between all cascade channels. Filter isolation adds to hybrid isolation when the pair of hybrids inputs are frequency separated.

Each hybrid ring cascade has two 50-ohm coaxial output lines. This is due to the power split character of the hybrid. Since the multicoupler unit is composed of two ring cascades, four 50-ohm coaxial outputs must be accepted by the antenna system used for maximum efficiency of operation. A compatible antenna is described herein; however, other antennas such as back-to-back rhombics for two-direction transmission may also be used.

A counter dial control may be provided for each of the sixteen channel matching filters. These tuning controls can be made autotune if desired by installing a line phase

discriminator, a transistor amplifier, and a size 18 servo motor for each channel. These components are commercially available.

Multicoupler performance monitoring may be provided by channel current metering and VSWR, i.e. voltage standing wave ratio, measurement at each hybrid. The multicoupler unit is designed to work into a maximum load VSWR of 3:1 at maximum power rating. Components are conservatively rated for forty kilowatt channel operation if the number of channels in use are limited. The coaxial lines used are two-inch outer conductor 50-ohm and 70-ohm sizes. Line stretches are employed which are capable of changing all line lengths twenty feet in each one hundred feet. These line stretchers may be adjusted to frequency settings and output line phasings during factory assembly checkout and remain at this setting.

It is noted that only high Q elements are used for all multicoupling and band combining circuitry. Since the hybrid rings and intercostal lines are constructed of low-loss air dielectric coaxial transmission lines, the efficiency is very high in the 2-30 megacycle communication bands.

The sectionalized antenna consists of two "discone" antennas stacked one above the other with the top section inverted.

The discone configuration is that of two conical sections joined base-to-base such that the lower cone is inverted. The two joined cones constitute the cage antenna which is used for the 2-8 megacycle band. The single cone at the top of the antenna is used for the 8-30 megacycle band. The discone has two feed points which are the top and bottom.

The impedance characteristics of both the cage and cone portions of the antenna are good. The VSWR of both, covering the 2-30 megacycle band, is 3:1 or better, referred to 50 ohms. No matching transformers are required for either section. There is no measurable interaction in the cone from the cage portion. The two stacked discone antennas form an omnidirectional sectionalized antenna which is 126 feet high and 34 feet, 2 inches at the maximum cage diameter. The active elements of the antenna are constructed of phosphor-bronze cable. The ground system uses sixty #8 copper radials 125 feet long. The sectionalized discone antenna requires four 50-ohm unbalanced feeder-lines for full bandwidth performance. Phasing of the feeder-lines to control antenna radiation angle is preset by the line stretchers for each hybrid nominal frequency in the multicoupler unit.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a system of the character described wherein it is desired to couple a plurality of transmitters to a single antenna, a first hybrid ring, a second hybrid ring, a first pair of transmitters each operating at a frequency somewhat different than a first nominal frequency and each being coupled to said first ring, a second pair of transmitters each operating at a frequency different than a second nominal frequency and each being coupled to said second ring, a transmitting antenna, and means coupling each of said rings to said antenna, said coupling means including connections between said first and second rings, said connections having an electrical length substantially equal to one-half of the wavelength of one of said nominal frequencies for isolating said first ring from said second ring.

2. A system as set forth in claim 1 in which said coupling means comprises a transmission line having a shorted end, and said first and second hybrid rings are coupled

to said transmission at points thereon one quarter of a wavelength of the operating frequency of the corresponding ring from said shorted end.

3. A system as set forth in claim 1 in which said coupling means from one hybrid ring to said antenna includes the other hybrid ring.

4. A system as set forth in claim 1 in which at least one of said transmitters is coupled to its corresponding ring through a transmission line having a grounded sheath and an inner conductor, a coil having one terminal grounded and a first tap thereon connected to said conductor, a second tap on said coil being connected to an arm of said ring through a series resonant circuit resonant to the frequency of said one transmitter.

5. In a coupling system of the character described, a first six quarter-wavelength hybrid ring at a first nominal frequency, a second six quarter wavelength hybrid ring at a second nominal frequency, each ring having two pairs of conjugate arms with each arm of a pair being isolated from the other arm of the same pair, a first pair of transmitters coupled respectively to said first ring through different arms of one conjugate pair thereof, a second pair of transmitters coupled respectively to said second ring through different arms of one conjugate pair thereof, an antenna, said antenna being coupled to the other pair of conjugate arms of each ring through connections having an electrical length substantially equal to one-half of the wavelength of one of said nominal frequencies for isolating said first ring from said second ring.

6. A system as set forth in claim 5 including a pair of transmission lines each having a shorted end and each having its other end coupled to an antenna, said other pair of conjugate arms of the first ring being coupled to corresponding opposite ones of said transmission lines one quarter of a wavelength of the nominal frequency of said first ring from the shorted ends thereof, said other pair of conjugate arms of the second ring being coupled to corresponding opposite ones of said transmission lines one quarter of a wavelength of the nominal frequency of said second ring from the shorted ends thereof.

7. A system as set forth in claim 5 in which one of said other pair of conjugate arms of said first ring is coupled to one of said other pair of conjugate arms of said second ring through a transmission line having one half

wavelength at the nominal frequency of said second ring, and said second ring having a frequency dependent three quarter wavelength section containing lumped reactances for preventing said other pair of conjugate arms of said second ring from being conjugate at frequencies substantially removed from the nominal frequency of said second ring.

8. A system as set forth in claim 6 in which the nominal frequency of one ring is a multiple of two of the nominal frequency of the other ring.

9. A system as set forth in claim 6 in which said rings, transmitters and transmission lines are duplicated to provide a second pair of transmission lines, and said antenna has a pair of sections each with a pair of terminals, each pair of said terminals being connected between transmission lines of different pairs thereof.

10. A system as set forth in claim 9 in which the first and second hybrid rings have a nominal frequency differing from each other by a factor of two with the nominal frequency of said duplicated hybrid rings differing from the nominal frequency of said first and second rings by a factor of 1.4.

11. A system as set forth in claim 9 in which said antenna comprises two cage-discone antenna sections.
